TRUING AND BALANCING DEVICE FOR A
FACE TYPE DIAMOND GRINDING WHEEL

Elmer Speicher, Birmingham, Mich.

Application September 8, 1950, Serial No. 183,800

7 Claims. (Cl. 51—168)

1

This invention relates to a truing and balancing device for a face type diamond grinding wheel, and more particularly to a novel construction associated with the grinding wheel by which the grinding surface thereof may be arranged in a plane at right angles to its axis of rotation.

It is the object of the present invention to provide an unusual and simplified construction in conjunction with a face type diamond grinding wheel to permit truing of the same.

It is a further object of the present invention to provide a balancing means in association with the truing means for minimizing vibration of said grinding wheel during rotation.

These and other objects will be seen from the following specification and claims in conjunction with the appended drawing in which—

Fig. 1 is an elevational section of a face type diamond grinding wheel as mounted upon its driving spindle, there being a truing indicator provided, and

Fig. 2 is a left end elevational view of the grinding wheel.

It will be understood that the above drawing illustrates merely a preferred embodiment of the invention and that other embodiments are contemplated within the scope of the claims hereinafter set out.

Referring to the drawing the present face type diamond grinding wheel includes the annular plate 11 having a central depression 11' and corresponding thereto the central plate 12. There is provided upon the peripheral portion of said grinding wheel an annular abrasive ring 13 which is intimately bonded and secured to annular plate 11 and which includes a conventional diamond abrasive surface wherein finely divided diamond particles are secured in the ring form 13 as shown in Figs. 1 and 2.

The present diamond grinding wheel 11—12—13 has a central aperture to receive the central projecting stem 14 of the rotatable wheel driving spindle 15, said spindle having an annular flange 16 adjacent its outer end and arranged at the inner end of the stem 14 as shown in Fig. 1.

Circular pack plate 17 has a central opening which similarly receives the stem 14 after which the central plate 12 of the grinding wheel is positioned upon said stem and immovably secured thereon by the nut 22 which engages the threaded portion 21 on the outer end of said stem.

The central plate 12 of the grinding wheel has a plurality of spaced circularly arranged tapped openings within which are threadably projected screws 18 as shown in Figs. 1 and 2.

2

In setting up the grinding wheel for testing the face 13 to determine whether all points upon its outer surface lie in the same plane at right angles to the axis of rotation of the spindle 15, said grinding wheel is arranged as shown in Fig. 1 with a suitable indicator 23 being provided. Said indicator is mounted upon a bracket 25 and includes the rotatable indicator arm 24, the lateral extension 26 and the actuating arm 27 which is arranged normally of the outer surface of the grinding surface 13. By setting the indicator with respect to and in slight contact with the surface of the grinding wheel, rotation of the latter will indicate whether its surface is true, and whether all points upon its surface lie in a plane normal to the axis of rotation of the driving spindle 15.

Variations in the surface 13 are corrected by adjusting the screws 18 selectively so that the inner ends thereof are in operative engagement with the inner surface of the back plate 17. These screws are turned placing portions of the wheel plate 12 under a slight bending moment until the wheel is so adjusted that rotation thereof with respect to the indicator arm 27 will show little or no variation on the indicator arm 24 with respect to the dial of said indicator.

When the grinding wheel has been properly adjusted so that its outer grinding surface 13 lies in a plane at right angles to the axis of rotation of spindle 15, then said grinding wheel has been properly trued, as shown by indicator 23.

Normally the grinding wheel is not completely balanced, and upon rotation thereof certain vibrations are set up. This counter-acted and overcome by applying one or more of the nuts 19 to the screws 18 placing the same selectively and locking the same in position upon one or more of the screws 18 by the lock nuts 20 which are also threaded upon the corresponding screw. It will be noted that the nut or nuts 19 are spaced from the interior wall of the central plate 12 of the grinding wheel so as not to interfere with the setting of the screw with respect to said central plate and the back plate 17.

By this construction there is provided a simplified truing and balancing device for the face type diamond grinding wheel such as is shown in the drawing.

It is contemplated that under some conditions the circular back plate 17 may be omitted if desired so that the rear surface of the grinding wheel bears directly against the forward flat surface of the flange 16 on spindle 15. Accordingly the inner ends of the screws 18 would operatively

bear against the flange 16, and by this arrangement the abrasive surface 13 of the grinding wheel 11 could be properly aligned. For instance where the diameter of the grinding wheel is such and the screws 18 are so placed as to register with the flange 16, then in such cases the plate 17 could be omitted.

Having described my invention reference should now be had to the claims which follow for determining the scope thereof.

I claim:

1. In combination, a face type diamond grinding wheel having an annular flat abrasive surface at right angles to its axis of rotation, a rotatable spindle upon which said wheel is centrally mounted and secured, a flat back plate secured upon said spindle and arranged at a right angle to its axis of rotation and against which said wheel bears, and a plurality of spaced circularly arranged set screws threadably projected through said wheel with their inner ends operatively engaging said back plate to the extent that the outer face of said grinding surface lies in a plane at right angles to the axis of rotation of said spindle.

2. In combination, a rotatable spindle, a central stem projecting axially therefrom, a circular back plate mounted upon said stem and arranged at right angles to the axis of said spindle, a face type diamond grinding wheel having an annular flat abrasive surface at right angles to its axis of rotation mounted and secured upon said stem and bearing against said back plate, and a plurality of spaced circularly arranged set screws threadably extending through transverse threaded apertures in said wheel and operatively bearing against said back plate for adjusting the inner face of said wheel with respect to said back plate so that said grinding surface lies in a plane at right angles to the axis of rotation of said spindle.

3. In combination, a rotatable spindle having a circular flange adjacent one end thereof at right angles thereto, a central stem projecting axially therefrom, a circular back plate mounted upon said stem and bearing against said flange, a face type diamond grinding wheel having an annular flat abrasive surface at right angles to its axis of rotation mounted and secured upon said stem and bearing against said back plate, and a plurality of spaced circularly arranged set screws threadably extending through threaded apertures in said wheel and adjustably and operatively bearing against said back plate for adjusting said wheel with respect thereto so that said grinding surface lies in a plane at right angles to the axis of rotation of said spindle.

4. In combination, a rotatable spindle having a circular flange adjacent one end thereof at right angles thereto, a central stem projecting axially therefrom, a circular back plate mounted upon said stem and bearing against said flange, a face type grinding wheel having an annular flat abrasive surface at right angles to its axis of rotation

mounted upon said stem and bearing against said back plate, a plurality of spaced circularly arranged set screws threadably extending through threaded apertures in said wheel and adjustably and operatively bearing against said back plate for adjusting said wheel with respect thereto so that said grinding surface lies in a plane at right angles to the axis of rotation of said spindle, said stem being exteriorly threaded, and a nut mounted upon said stem and operatively bearing against said grinding wheel for securing the same on said spindle.

5. In combination, a rotatable spindle, a central stem projecting axially therefrom, a circular back plate mounted upon said stem and arranged at right angles to the axis of said spindle, a face type diamond grinding wheel having an annular flat abrasive surface at right angles to its axis of rotation mounted and secured upon said stem and bearing against said back plate, a plurality of spaced circularly arranged set screws threadably extending through transverse threaded apertures in said wheel and operatively bearing against said back plate for adjusting the inner face of said wheel with respect to said back plate so that said grinding surface lies in a plane at right angles to the axis of rotation of said spindle, and nuts selectively mounted and secured upon some of said set screws for balancing said wheel against vibration upon rotation thereof.

6. In combination, a rotatable spindle having a circular flange adjacent one end thereof at right angles thereto, a central stem projecting axially therefrom, a face type diamond grinding wheel having an annular flat abrasive surface at right angles to its axis of rotation mounted and secured upon said stem and bearing against said flange, and a plurality of spaced circularly arranged set screws threadably extending through threaded apertures in said wheel and adjustably and operatively bearing against said flange for adjusting said wheel with respect thereto so that said grinding surface lies in a plane at right angles to the axis of rotation of said spindle.

7. In combination, a rotatable spindle having a circular flange adjacent one end thereof at right angles thereto, a central stem projecting axially therefrom, a face type diamond grinding wheel having an annular flat abrasive surface at right angles to its axis of rotation mounted and secured upon said stem and bearing against said flange, a plurality of spaced circularly arranged set screws threadably extending through threaded apertures in said wheel and adjustably and operatively bearing against said flange for adjusting said wheel with respect thereto so that said grinding surface lies in a plane at right angles to the axis of rotation of said spindle, and nuts selectively mounted and secured upon some of said set screws for balancing said wheel against vibration upon rotation thereof.
